UNITED STATES PATENT OFFICE.

LÉON PAUL CONARD, OF LONDON, ENGLAND, ASSIGNOR OF ONE-HALF TO CHARLES FERDINAND VEIT AND GEORGE DICKMAN, BOTH OF SAME PLACE.

BUTTON.

SPECIFICATION forming part of Letters Patent No. 327,768, dated October 6, 1885.

Application filed March 6, 1885. Serial No. 157,952. (No model.)

To all whom it may concern:

Be it known that I, LÉON PAUL CONARD, a citizen of the Republic of France, residing at London, England, have invented new and useful Improvements in Buttons, of which the following is a specification.

My invention relates to improvements in cuff-buttons or the like; and it consists in the combination, with a button-head and a hollow or slotted shank secured thereto, of an elastic rod, a spring-supported cap formed on said rod, push-pieces in the button-head constructed to engage the spring-supported cap, and a leaf or leaves hinged to the shank and pivoted to the elastic rod. In the button-head are formed suitable guideways, the push-pieces fitting in said guideways and extending out beyond the edge of the button-head, and the spring-supported cap extends into the button-head in position to be acted upon by the push-pieces. When two leaves are used, the elastic rod is forked.

In the accompanying drawings, Figure 1 represents a vertical section of my improved button in the plane $y y$, Fig. 3, showing the leaves extended. Fig. 2 is an end elevation, with part broken away, showing the leaves folded. Fig. 3 is an inverted plan view of Fig. 1. Fig. 4 is a side elevation with the leaves folded. Fig. 5 is a plan view with the top removed, showing the leaves extended. Fig. 6 is a detached elevation of the spring-supported cap and elastic rod.

Similar letters indicate corresponding parts. In the drawings, the letter A designates the button-head, to which is rigidly attached a slotted shank, B, which shank may, however, be made hollow or otherwise.

B' is a forked elastic rod, on one end of which is formed or secured a cap, C, which extends through a suitable aperture, a, into the button-head A, in position to be acted upon by push-pieces D D', which slide in a suitable guideway, b, formed in the button-head, and extend out beyond the edge of the same through apertures c c', formed therein. The cap C is supported upon a spiral spring, E, which surrounds the

elastic forked rod B', and rests on suitable ledges, d d', formed on the lower end of shank B.

The button-head A is made hollow and of any suitable material, and, as shown in the drawings, the guideway b is formed by blocks f f', secured therein, and that part of the push-pieces D D' which extends out beyond the edge of the button-head is not as wide as the remainder, whereby they are prevented from falling out.

The inner or adjacent ends of the slides D are mounted or beveled on their under sides, and the opposite sides of the cap C are convex or beveled, to be acted upon by the adjacent ends of the slides in such manner that by pushing the slides inward the cap C will be depressed, and the leaves or shoes G G' thereby brought parallel, or approximately so, as in Fig. 2.

The head is closed by a disk, F, which is secured, together with the blocks, to the button-head; or the blocks may be formed integral with the head and the same closed by a stone or disk, as before.

G G' are the leaves, which are hinged to the lower end of the shank B at h h' and i i', and pivoted to the prongs of the elastic forked rod B' at l l'. If only one leaf is to be used, the same is hinged to the shank, as before, but the rod B' is not forked.

Since the spring-supported cap rests upon a spring which acts continually against it, the normal position of the button is as shown in Figs. 1 and 3, in which position the leaves are extended or brought into a plane parallel to the plane of the button-head. If the button described is designed to be used as a cuff-button, and it is desired to apply the same to a cuff, the push-pieces are pressed inwardly and so held, whereby the spring-supported cap is depressed, together with the forked rod attached or formed integral therewith, and the leaves are folded. The button can now be inserted into the button-holes, and on releasing the push-pieces the leaves are extended, and the button is held in place by the same.

If desired, the push-pieces may be inclined

on both top and bottom, overlapping each other at their ends, and also the spring-supported cap, whereby the cap will be depressed, as before, when the push-pieces are pressed inward.

What I claim as new, and desire to secure by Letters Patent, is—

1. The combination, with a button-head and a hollow or slotted shank secured thereto, of the elastic rod B', the spring-supported cap C, formed on or secured to said rod, the push-pieces D D' in the button-head, constructed to engage the spring-supported cap, and the leaf or leaves hinged to the shank and pivoted to the elastic rod, substantially as and for the purpose specified.

2. The combination, with the button-head and the hollow or slotted shank secured thereto, of the guideway b, formed in the button-head, the push-pieces D D', which fit in the guideway and extend out beyond the edge of the button-head, the forked elastic rod B', the spring-supported cap C, formed on or secured to said rod and extending into the button-head in position to be acted on by the push-

pieces, the leaves hinged to the shank and pivoted to the elastic rod, and the disk which closes the button-head, substantially as shown and described.

3. The combination, with the button-head 30 and the hollow or slotted shank secured thereto, of the guideway b, formed in the button-head, the push-pieces D D', which fit the guideway and extend out beyond the edge of the button-head, the elastic rod, the spring-supported cap 35 C, formed on or secured to said rod, and extending into the button-head in position to be acted on by the push-pieces, and the leaf hinged to the shank and pivoted to the elastic rod, substantially as shown and described. 40

In testimony whereof I have hereunto set my hand in the presence of two subscribing witnesses.

LÉON PAUL CONARD.
